UNITED STATES PATENT OFFICE.

MAX KAMAN, OF SYRACUSE, NEW YORK.

RADIATOR FOR AUTOMOBILES.

1,149,772.

Specification of Letters Patent. Patented Aug. 10, 1915.

Application filed March 8, 1913. Serial No. 752,865.

To all whom it may concern:

Be it known that I, MAX KAMAN, a citizen of the United States, residing at Syracuse, in the county of Onondaga and State of New York, have invented certain new and useful Improvements in Radiators for Automobiles, of which the following is a specification.

This invention relates to improvements in radiators, of the class employed for cooling the water which protects the cylinders of automobile motors, and has for its object to provide a novel, simple and effective water cooler, wherein a greater radiating surface is provided for a given quantity of water, thereby more readily and more quickly cooling the water, than under any other apparatus known to me. And a further object is to provide a radiator of the class, which is sectional, and wherein each section is capable of being applied, removed or replaced without disturbing the other sections.

The various features, as well as, the parts of the invention will be understood from the detailed description which follows, wherein reference is made to the accompanying drawings, in which—

Figure 1 is a front elevation of the complete radiator. Fig. 2 is a horizontal section taken on line 2—2 of Fig. 1. Fig. 3 is an enlarged vertical section, taken on line 3—3 of Fig. 2. Fig. 4 is an enlarged central vertical cross-section on line 4—4 of Fig. 1. Fig. 5 is a rear side elevation of the complete device. Fig. 6 is an isometric view, showing the construction and arrangement of the radiating parts; also showing the method of applying the same to the frame.

Similar characters of reference are assigned to corresponding parts throughout the several views.

The drawings illustrate one form of my improved radiator, in which 2 represents a hollow frame or body, having relatively large front and rear openings 3 and 4, which correspond in location, size and shape.

5 represents a filling spout or neck which is disposed at the top of the body 2, by means of which the water for cooling the motor-cylinders (not shown) is supplied. The hot water is carried from the motor to the top portion of the radiator by means of a tube or pipe 6. After the water is cooled it is carried back to the motor by a pipe 7, which draws the water from near the bottom

of the radiator. The cooling of the water is accomplished by means of a series of tubes or flues, which are preferably square and grouped in similar detachable sections, as 8, 9, 10 and 11, each of which consists of similar front and back plates or heads 12 and 13, and a number of the tubes 15, which are preferably horizontally disposed. The plates 12 and 13 have a relatively large number of coinciding perforations 14, in which the tubes 15 are inserted, for providing as many normally open flues through which the air passes during the travel of the car. The tubes 15 of each of the sections are spaced equi-distantly, preferably in vertical and horizontal rows, as shown, and the tubes are preferably held by the plates 12 and 13 so as to provide clear spaces 15' of one-sixteenth to one-eighth of an inch between the adjacent tubes, which spaces are filled with the hot water as it gravitates from the top to the bottom of the tank 2. The several sections 8, 9, 10 and 11 when placed in the frame substantially close or fill the central openings 3 and 4, and together comprise but a single radiating field, as there are no barriers or partitions between the flues of the adjacent sections. The water, whether entering the radiator through the filling tube 5, or the pipe 6, falls upon the topmost tier of the radiating flues 15, of the section 8, and thence circulates or flows around and between all of the flues of the several sections, until it finally reaches the free or clear space (2') in the bottom of the tank, from which it discharges through the pipe 7. The corresponding plates 12 and 13 of the several sections of the radiator, when the latter are placed in the frame 2, preferably align with each other and also with the free lateral edges of the frame openings 3 and 4.

To render the joints between the sections, as well as between the ends of the section plates 12 and 13 and the frame 2 water tight, each of said joints is preferably covered with strips of thin metal 16 and 17, which are preferably soldered in place.

To disconnect one or more of the radiating sections for repairs, the strips 16 and 17 may be readily and quickly removed from the front and back, by the use of a common soldering iron, after which the sections may be withdrawn, as shown by dotted lines in Fig. 4.

The tank or body 2 is protected by a band-like casing or shield 18, which sur-

rounds the lateral edges and also partially overlaps and gives a finished appearance to the top and the sides of the front of the radiator.

5 The top of the casing 18 is provided with a tubular part 22, which serves as a shield for the filling tube 5, and 23 represents a screw-cap which closes the part 22, and also the mouth of the tube 5, by means of a ball-like part 23'. The casing or jacket 18 is detachably secured to an angular metal part 19 by bolts 20, and the part 19 is preferably permanently secured to the rear face of the tank 2 by solder which is applied at 21. 10 The flanged part 19 preferably projects beyond the rear face of the radiator a sufficient distance to receive and support one end of the usual hood (not shown) of a car. The clear space 2' of the body 2 which surrounds the radiator sections is provided for holding an additional supply of water, so as to obviate the necessity of frequent replenishing of the cooling system.

15 My improved radiator is extremely simple, and owing to the number and close arrangement of the flues 15, it is capable of quickly and effectively cooling the water it receives from the motor cylinders.

20 The provision of a large number of radiating tubes 15, which are arranged to divide the body of the hot water into relatively thin sheets or columns, affords a greater amount of radiating surface, without occupying any more space, than any of 25 the older styles of radiators, known to me. And furthermore, the grouping or arrang-

ing of the radiating tubes into sections of convenient size, which are readily detachable in case of leakage or injury to any of the tubes, is an essentially novel feature 40 which enhances the value of my improvement.

Having thus described my invention, what I claim as new and desire to secure by Letters Patent, is—

45 In a sectional radiator, the combination of a plurality of sections, each section comprising spaced front and back plates, said plates having coinciding perforations, and a series of tubes spanning the space between 50 said plates, the ends of the tubes being disposed in the corresponding perforations and being flush with the outer faces of said plates, the respective walls of the tubes being spaced equi-distantly from the walls of 55 the adjacent tubes, whereby to provide vertical and horizontal columns of water of the same thickness surrounding each tube, the said radiator sections being disposed horizontally, and the front and back plates of 60 the respective sections projecting above and below the walls of the tubes of the respective sections and adapted to be connected to one another, whereby to provide a water space of substantial area between the tubes of the 65 adjacent sections.

In testimony whereof I affix my signature in presence of two witnesses.

MAX KAMAN.
